UNITED STATES PATENT OFFICE.

EDWARD P. RICH, OF CHICAGO, ILLINOIS.

HEATING SYSTEM.

1,338,961.

Specification of Letters Patent. Patented May 4, 1920.

Application filed January 30, 1919. Serial No. 274,007.

To all whom it may concern:

Be it known that I, EDWARD P. RICH, a citizen of the United States, residing at Chicago, in the county of Cook and State of Illinois, have invented a certain new and useful Improvement in Heating Systems, of which the following is a specification.

My invention relates to heating systems, more particularly steam-heating systems in which the steam supply pipe leads from a point above the radiator. It will be understood by those skilled in the art of heating that it frequently happens that the steam supply pipes are necessarily located overhead. This is true for example, in the average one story factory building where the floor is laid directly upon the ground and no basement is available for below-floor piping. In such cases the heating main is hung overhead near the roof and runs the length of the building with drop pipes at suitable intervals for the individual radiators. The valve for controlling the flow of steam to any particular radiator is naturally located at the radiator and not at the steam main for the reason that if located at the latter point it would be out of reach of the attendant. But serious difficulty has arisen in connection with this very common type of installation on account of the condensation which occurs in the down-pipe when the radiator valve is shut off. As the steam after condensation occupies but a small fraction of the space it originally occupied, fresh steam from the main lead comes in to take its place, and this action continues until frequently the entire down-pipe is filled with water. The result is that the water in the down-pipe frequently freezes with the usual damaging results. The object of my invention is to provide means whereby it becomes possible to turn the heat onto or off of the radiator as may be desired and at the same time keep the down-pipe thoroughly drained. Viewed in another aspect, it is my object to do away with extra piping for drainage purposes. According to my invention the condensation from the drop riser or down pipe passes through the radiator and through piping which is necessary for the radiator itself, and in my system this condensation passes through whether the radiator valve is open or shut. The automatic portion of my compound valve is not called upon to operate when the steam is turned on. It is when the radiator is shut off that

the automatic feature comes into play. Heretofore drainage has been provided for only by the aid of cumbrous and expensive extra connections, which are totally dispensed with in my system. As will herein-after appear, in my system the automatic valve is thermally controlled and the thermo sensitive element is at all times subject to the fluid on the inlet side of the main valve and yet, when the automatic valve is open, it passes the fluid to the discharge side of the main valve. I accomplish my object by the construction illustrated in the accompanying drawings, in which

70

Figure 1 is a diagrammatic view showing a typical installation in a saw tooth factory building.

Fig. 2 is an elevation of the valve employed, the view being taken on the line 75 2-2, Fig. 3.

Fig. 3 is a sectional elevation on the line 3-3, Fig. 2.

Fig. 4 is a plan section on the line 4-4, Fig. 3.

80

Fig. 5 is a general perspective view of a typical form of installation, as in Fig. 1.

Fig. 6 is a sectional elevation on the line 6-6 Fig. 3.

Like numerals denote like parts throughout the several views.

Referring to the diagram, 1 represents the horizontal steam main which is located near the upper portion of the room—in this case near the roof 2. It will be understood that this steam main runs the entire length of the building or such portion thereof as is to be heated by it. Leading to each of the radiators 3 is a lateral 4 connected to a down-pipe 5 for supplying the radiator. Referring now more particularly to Figs. 2 and 4 which illustrate the preferred valve construction, 7 represents a valve casing provided in the present case with an internally threaded hub 8 adapted to receive a nipple 9 connected by means of an elbow 10 to the lower end of the down-pipe 5. Within the valve casing 7 is an internal wall 12 having an annular opening at the top into which screws a valve seat 13 adapted to coöperate with the main shut-off valve 14 which is here shown as being arranged horizontally. It will be understood however that any of the well known types of shut-off valves may be employed with like effect. It will also be understood that in some cases the ring 13 may be omitted, permitting the main valve

90

to seat upon one of the integral portions of the casing. Valve 14 is controlled by a threaded stem 15 passing through a suitable stuffing box composed of the parts 16, 17, 18 5 or any suitable substitute therefor. A hand wheel 20 is provided for rotating the stem. At the outlet end of the valve casing is an internally threaded hub 22 which takes the threaded end of the pipe 23 which leads to 10 the radiator. A return pipe 24 shown in the diagram, Fig. 1, conveys the waste steam and water away from the radiator. It is here shown as being beneath the floor, which conforms to well recognized practice.

15 At the side of the valve casing, opposite to the internal wall 12, is a by-pass having two principal chambers 25, 26. These are separated by a wall 27 at the upper end of which is an annular opening supporting a 20 valve seat 30, best shown in Fig. 3. This is adapted to coöperate with the valve proper 31 of a thermal expansion trap, having a so called "bellows" 32 suspended from a cap 33 screwing down into the top of the by-pass.

25 Traps of this kind are well known and for the present purpose it is sufficient to say that the device is so constructed that beneath the predetermined critical temperature the "bellows" will remain contracted and hold 30 valve 31 away from its seat. When the critical temperature is reached or exceeded the "bellows" expands and lowers the valve onto its seat, thus shutting off the passage-way. In my device I so arrange and construct the thermal trap that the valve 31 35 will remain open unless subjected to the temperature of steam. Consequently, the valve will remain open and permit water to pass but will close as soon as it becomes enveloped 40 in steam. By preference the by-pass 25, 26 is in semi-circular form when viewed in plan as in Fig. 4. By preference it is also located at or near the bottom of the valve casing.

45 In operation, when the apparatus is installed in the manner described, if the main valve 14 is open, the steam from the main 1, lateral 4 and down-pipe 5 will have a practically unobstructed flow through the 50 valve casing and into the radiator. But if the heat of the radiator is not desired the attendant closes the main valve 14. So long as the internal parts of the valve casing remain at or above the boiling point of water the 55 thermal valve 31 will remain closed. As the parts cool off, however, especially the lateral 4 and down-pipe 5, water will begin to collect in the bottom of the valve casing 7. As soon as this reaches the "bellows" the latter 60 will contract and open valve 31 and permit the water to pass off through the passage 26 and into the outlet 24. But as soon as the water has passed and steam commences to flow the "bellows" will immediately close 65 the valve. Consequently, the down-pipe

will be kept free of water and at the same time no appreciable amount of steam will be permitted to enter the radiator. Thus the radiator will be kept cold and at the same time it and the pipes leading to it will 70 be kept clear of water. Consequently the attendant will have the same control over the radiator that he would with an ordinary valve, but he is relieved of the necessity of watching to see that water does not collect. 75 Ordinarily, in freezing weather it would be necessary for him to open the main valve from time to time to prevent danger of freezing, but by installing my apparatus no attention is necessary. It will be noted 80 that in my system the thermo-sensitive element of the automatic valve is on the supply side of the main valve and on the supply side of the automatic valve—that is—it is at all times adapted to 85 be influenced by the temperature of the fluid (whether water or steam) in the down pipe or "drop riser." Nevertheless, when the automatic valve is open it will permit water to pass the main valve whether the latter is open or closed. My apparatus also economizes steam for the reason that when the operator opens the main valve he necessarily lets a considerable quantity of steam 90 pass into and through the radiator. With my system steam is never admitted in any appreciable quantity except when the main valve is open. My system also prevents "water hammer" for if the water in the radiator backs up to the level of the "bellows" 95 the "bellows" will open and hence subject the water in the radiator to steam pressure which will drive the water out.

It will be noted in Fig. 1 that the lateral leads out of the bottom of the main 1. This 105 affords means for draining the main when desired.

I do not herein claim the valve casing and parts within it specifically as they form the subject of a divisional application filed 110 March 20th, 1920 Serial No. 367,549.

Having thus described my invention what I claim as new and desire to secure by Letters Patent, is:—

1. A heating system having a radiator, an 115 overhead source of steam supply, a main shut off valve interposed between them, a by pass leading around said valve, and a thermally controlled valve in said by pass subject to the action of the fluid on the supply side of said thermally controlled valve. 120

2. Heating apparatus comprising a radiator, a steam supply main above said radiator, a down-pipe leading from said supply main to the radiator, a valve casing forming 125 a connection between the down-pipe and the radiator, said valve casing having a main shut-off valve, a by-pass around said valve, and a valve in said by-pass adapted to open in the presence of water and close in the 130

presence of steam appearing on the supply side.

3. Heating apparatus comprising a radiator, a steam supply main above said radiator, a down-pipe leading from said supply main to the radiator, a valve casing forming a connection between the down-pipe and the radiator, said valve casing having a main shut-off valve, a by-pass emerging from the side of the casing on the supply side of the main valve and at a point near the bottom of the casing, said by-pass making a return bend and reentering the casing at a point on the discharge side of the main shut-off valve, and a thermally controlled valve for controlling the flow through said by-pass, said thermally controlled valve being adapted to be influenced at all times by the fluid on the supply side thereof.
- 10 4. Heating apparatus comprising a radiator, a steam supply main above said radiator, a down-pipe leading from said supply main to the radiator, a valve casing forming a connection between the down-pipe and the radiator, said valve casing having a main shut-off valve, a by-pass emerging from the side of the casing on the supply side of the main valve and at a point near the bottom of the casing, said by-pass making a return bend and reentering the casing at a point on the discharge side of the main shut-off valve, and a thermally controlled valve for controlling the flow through said by-pass, said thermally controlled valve being adapted to be influenced at all times by the fluid on the supply side thereof.
- 15 5. Heating apparatus comprising a radiator, a steam supply main above said radiator, a down-pipe leading from said supply main to the radiator, a valve casing forming a connection between the down-pipe and the radiator, said valve casing having a main shut-off valve, a by-pass emerging from the side of the casing on the supply side of the main valve and at a point near the bottom of the casing, said by-pass making a return bend and reentering the casing at a point on the discharge side of the main shut-off valve, and a thermally controlled valve for controlling the flow through said by-pass, said thermally controlled valve being adapted to be influenced at all times by the fluid on the supply side thereof.
- 20 6. A heating system having a radiator, a down-pipe chiefly above said radiator and leading thereto from a source of steam supply, a valve casing interposed between the downpipe and the radiator and two valves in said casing, one being the main shut off valve and the other being an automatic valve adapted to close in the presence of steam and open in the presence of water, said automatic valve communicating with the casing on the supply side of the main valve and also on the discharge side thereof, whereby it may pass water even though the main valve is closed and the device as a whole may pass either steam or water if the main valve is open, regardless of whether the automatic valve is open or closed.
- 25 7. Heating apparatus comprising a radiator, a steam supply main above said radiator, a down-pipe leading from said supply
- main to the radiator, a valve casing forming a connection between the down-pipe and the radiator, said valve casing having a main shut-off valve, a by-pass emerging from the side of the casing on the supply side of the main valve and at a point near the bottom of the casing, said by-pass making a return bend and reentering the casing at a point on the discharge side of the main shut-off valve, the point of reentry being near the bottom of the valve casing, and a thermally controlled valve for controlling the flow through said by-pass, said thermally controlled valve being near the bottom of the valve casing, and a thermally controlled valve for controlling the flow through said by-pass, said thermally controlled valve being adapted to be influenced at all times by the fluid on the supply side thereof.
- 30 8. Heating apparatus comprising a radiator, a steam supply main above said radiator, a down-pipe leading from said supply main to the radiator, a valve casing forming a connection between the down-pipe and the radiator, said valve casing having a main shut-off valve, a by-pass emerging from the side of the casing on the supply side of the main valve and at a point near the bottom of the casing, said by-pass making a return bend and reentering the casing at a point on the discharge side of the main shut-off valve, and a thermally controlled valve for controlling the flow through said by-pass, said thermally controlled valve being adapted to be influenced at all times by the fluid on the supply side thereof.
- 35 9. Heating apparatus comprising a radiator, a steam supply main above said radiator, a down-pipe leading from said supply main to the radiator, a valve casing forming a connection between the down-pipe and the radiator, said valve casing having a main shut-off valve, a by-pass emerging from the side of the casing on the supply side of the main valve and at a point near the bottom of the casing, said by-pass making a return bend and reentering the casing at a point on the discharge side of the main shut-off valve, and a thermally controlled valve for controlling the flow through said by-pass, said thermally controlled valve being adapted to be influenced at all times by the fluid on the supply side thereof.
- 40 10. Heating apparatus comprising a radiator, a steam supply main above said radiator, a down-pipe leading from said supply

In witness whereof, I have hereunto subscribed my name.

EDWARD P. RICH.
